UNITED STATES PATENT OFFICE

HERBERT H. WYDOM, OF BOSTON, MASSACHUSETTS, ASSIGNOR TO HOOD RUBBER COMPANY, INC., OF WATERTOWN, MASSACHUSETTS, A CORPORATION OF DELAWARE

DESIGN FOR A COMBINED SOLE AND HEEL

Application filed September 21, 1929. Serial No. 32,828. Term of patent 7 years.

To all whom it may concern:

Be it known that I, HERBERT H. WYDOM, a citizen of the United States, residing at Boston, in the county of Suffolk and Commonwealth of Massachusetts, have invented a new, original, and ornamental Design for a Combined Sole and Heel, of which the following is a specification, reference being had to the accompanying drawing, forming part thereof.

Referring to the drawing:

Figure 1 is a plan view of a combined sole and heel, showing my new design.

Fig. 2 is a sectional elevation taken on line 2—2, Fig. 1.

Fig. 3 is a sectional elevation taken on line 3—3, Fig. 1.

I claim:

The ornamental design for a combined sole and heel, as shown.

HERBERT H. WYDOM.
